UNITED STATES PATENT OFFICE.

ANSELMO SIMONCELLI, OF BUTTE, MONTANA.

SELF-LEVELING TABLE.

1,248,734.

Specification of Letters Patent.

Patented Dec. 4, 1917.

Application filed April 17, 1917. Serial No. 162,594.

To all whom it may concern:

Be it known that I, ANSELMO SIMONCELLI, a subject of the King of Italy, residing at Butte, in the county of Silverbow and State 5 of Montana, have invented certain new and useful Improvements in Self-Leveling Tables, of which the following is a specification.

This invention relates to certain new and 10 useful improvements in self-leveling tables.

The primary object of the invention is the provision of a table structure adaptable for use upon shipboard arranged for automatically maintaining the top of the table horizontally positioned regardless of the rolling 15 and tossing of the ship under varying weather conditions.

A further object of the device is the provision of a table having the top arranged 20 normally horizontal, provision being made for anti-frictionally mounting the table top in a resilient manner for purposes of equalizing while the top may also be maintained stationary when found desirable.

With these general objects in view and others that will appear as the nature of the invention is better understood, the same consists in the novel construction, combination and arrangement of parts hereinafter more 30 fully described, illustrated in the accompanying drawings, and then claimed.

In the drawing forming a part of this application and in which like designating characters refer to corresponding parts 35 throughout the several views:—

Figure 1 is a vertical longitudinal sectional view through the device.

Fig. 2 is a horizontal sectional view taken upon line II—II of Fig. 1, with two of the 40 positioning members in their locked arrangement.

Fig. 3 is an enlarged detail sectional view taken upon line III—III of Fig. 2, and,

Fig. 4 is a horizontal sectional view taken 45 upon line IV—IV of Fig. 3.

The preferred embodiment of the invention mainly consists of a rectangular frame 10 having squared corner posts or legs 11 upon the tops of which posts a table top 12 is resiliently mounted by means of springs 13 while a conical weight 14 is connected beneath the table top by diametrically arranged chains 15 having their upper ends attached as at 16 to the said top 12.

55 A depending side rail 17 is carried by the top 12 inclosing the upper portion of the

frame 10 as well as the springs 13 and being provided with pivoted locking levers 18 at convenient points upon its lower edge for engaging within arcuate notches 19 in the 60 adjacent faces of the legs 11. The levers 18 are substantially the same width as the rail 17 for positioning in alignment therewith when not in use. It will be understood that the central depending weight 14 65 normally maintains the table top 12 substantially horizontal when the levers 18 are released regardless of the slight tipping of the frame 10 by reason of the movement of the deck 20 or other support upon which the 70 table is mounted.

The springs 13 are anti-frictionally journaled between the posts 11 and the table top 12, each of the said springs having a positioning cap 21 at each end thereof 75 mounted upon balls 22 carried by plates 23 and arranged with retaining rings 24 overlying the said caps and attached to the posts 11 and top 12 by means of screws 25.

It will be seen that the side tipping or 80 inclination of the springs 13 allows the caps 21 to slightly revolve within the said ball bearing members whereby a more perfect maintenance of equilibrium is rendered possible than with rigidly anchored spring- 85 mounting members.

A serviceable table for ships is arranged in which the top 12 is normally maintained horizontal, the action of the positioning weight 14 being easily and quickly accomplished while by means of the locking levers 18, the top may be rigidly secured when desired.

What I claim as new is:—

1. A ship's table comprising a frame, a 95 top arranged thereabove, resilient supporting connections between the said frame and top anti-frictionally journaled to said frame and top, and a counter-balancing weight suspended from said top.

2. A device of the class described comprising a frame having corner legs, a top positioned above the said legs, bearing plates carried by the tops of said legs and by opposite portions of the said top, mounting caps 105 anti-frictionally supported upon the said plates, helical springs secured between the said caps, and a centrally depending positioning weight attached to the said top.

3. A device of the class described comprising a frame having corner legs, a top positioned above the said legs, bearing plates

carried by the tops of said legs and by opposite portions of the said top, mounting caps anti-frictionally supported upon the said plates, helical springs secured between the 5 said caps, a centrally depending positioning weight attached to the said top, a depending portion carried by said top surrounding the said springs and the upper portion of the frame, the said legs having re-

ceiving notches adjacent their upper ends, 10 and locking levers pivoted to the lower edge of said depending top portion adapted for seating within the said notches when the top is in its stationary position.

In testimony whereof I affix my signature.

ANSELMO SIMONCELLI.
